UNITED STATES PATENT OFFICE.

CHARLES F. PHILLIPS, OF ST. PAUL, MINNESOTA.

COLLAR-EDGING MACHINE.

1,324,169.

Specification of Letters Patent.

Patented Dec. 9, 1919.

Application filed November 11, 1918. Serial No. 261,955.

To all whom it may concern:

Be it known that I, CHARLES F. PHILLIPS, a citizen of the United States, residing at St. Paul, 391 E. 6th St., in the county of 5 Ramsey and State of Minnesota, have invented certain new and useful Improvements in Collar-Edging Machines, of which the following is a specification.

This invention relates to improvements in 10 collar edging machines and particularly to the type wherein the collar is held firmly on a form and the edging device is caused to roll over the edge of the collar.

One of the objects of the invention is to 15 provide improved means for polishing the inner face adjacent the upper edge of the collar to render it smooth without polishing the top of the collar. A further object of the invention is to provide ironing means 20 whereby the seam on the inner face of the neckband of the collar adjacent the upper edge thereof may be subjected to frictional action while the top of the edge is subjected to a rolling action.

25 A further object of the invention is to provide improved means for edging collars without subjecting the collar to undue heavy pressure as is customarily the case.

The invention consists in the construction, 30 combination and arrangement of parts hereinafter described and claimed.

Referring to the drawings,

Figure 1 is a perspective view of a collar edging machine embodying the invention.

35 Fig. 2 is a plan view of the edging device mounted on the collar holding form.

Fig. 3 is a perspective fragmentary view of the driving mechanism for actuating the device.

40 Fig. 4 is a fragmentary side view of the invention partly in section.

Fig. 5 is a vertical sectional view of a detail.

Fig. 6 is a fragmentary sectional view of 45 the form showing the collar resting thereon.

Figs. 7 and 8 are vertical sectional views of a double fold collar.

Fig. 9 is a vertical sectional view through 50 the upper edge of a double fold collar showing a fragment of the edging device.

Fig. 10 is a partially diagrammatic view showing the point of application of the edging device on the collar and Figs. 11 and 12 are diagrammatic views setting forth the 55 tripping means in the driving mechanism.

Referring to the drawings (Fig. 1) A represents the frame supporting the edging

device and comprises a base 1 upon which are rigidly mounted collar supporting forms 2. The forms comprise cylindrical members 60 axially vertically disposed and have a rounded upper edge 3. Rotatable in the frame and centrally disposed relative to said cylindrical members, is the shaft 4 carrying rigidly at its lower end the worm gear 5 and at 65 its upper end the edging mechanism B.

Journaled at each of its ends in the frame A is a power driven shaft 6 rigidly carrying a pulley 7 whereby said shaft may be driven from any suitable source of power such as 70 the motor C.

In Fig. 1 is shown a pair of edging devices, the cylindrical members 2 being suitably separated on the top of the base 1, the two cylindrical members alining with the 75 shaft 6 so that the worms 8 rotatable thereon mesh with the teeth of said worm gears 5 to drive the shafts 4 in a manner hereinafter to be explained. Since the actuating mechanism for each of the edgers is similar, a single complete device will hereinafter be described, it being understood that any number of edging devices may be mounted on an extended base and driven from a single shaft such as 6, each edging device having 80 its corresponding worm thereon. Slidably mounted on the shaft 6 by means of the feather 11 is the clutch member 12, having a median groove 13 and a laterally projecting pin 14 adapted to engage a similar pin 15 90 projecting laterally from the end of the worm, whereby, when the clutch 12 is slid toward said worm the engagement of the pins 14 and 15 will cause the worm to turn and actuate the gear 5. A collar secured on 95 the shaft holds the worm in position.

Pivottally mounted in the frame A as by means of pivot 16 and adapted to swing in a horizontal plane is the bell crank 17 having one of its arms directed upwardly 100 through the slot 18 in the top of the base 1, and terminating with a finger piece 19, whereby the lever may be manually rotated about its pivot. The other arm of the bell crank is adapted to movably fit with its 105 outer end into the groove 15 of the clutch member so that when the bell crank is manually moved the clutch member will be slid along the shaft 6.

Integral with the clutch moving arm and 110 projecting downwardly therefrom is a lug on the side of which is secured a spring arm 20. Pivottally mounted on the upper face of the gear 5 is the double ended tripping dog

21 adapted to engage said spring arm, as indicated in Figs. 11 and 12, wherein (Fig. 12) the block is shown engaging the arm to push it outwardly, to move the clutch member 12 out of engagement with the worm 8.

In Fig. 11 the dog is shown in the position it assumes just after passing the arm, it being evident that in the next revolution of the wheel 5 the dog will assume the position shown in Fig. 12 as it will be engaged by the arm 20 to turn it from the position shown in solid lines (Fig. 11) to the position shown in dotted lines, same figure. Thus the clutch member is actuated each alternate revolution of the gear 5. The edging mechanism B comprises an extension member 22, set-screwed on the upper end of the shaft 4. Said extension member being formed with a pair of outwardly extended bosses disposed in horizontal alinement to constitute pivots 23. The upper portion of the extension member is formed with a stuffing box, adapted to receive the gas supply pipe 23, the latter being surrounded by the threaded gland 24 which screws into said stuffing box and is adapted to compress a packing surrounding said pipe to render it tight against leakage.

The extension member is also provided with a side gas outlet 25 which is in open communication with the pipe 23, so that gas may pass therethrough.

Mounted in the pivots 23 so as to swing in a vertical plane and extending upwardly and outwardly over the cylindrical form 2 is the housing D. The housing D comprises an open work circular casing 26, having a centrally mounted spindle 27 whereon is rotatably mounted the edging wheel 28.

Integral with the casing and extending downwardly and inwardly and journaled on the pivots 23 are the arms 29. The arms 29 are symmetrically disposed about a radial line relative to the cylindrical forms 2, the open work casing being joined to the arms at their outer ends, in a manner to bring the longitudinal axis of the spindle 27 at an acute angle with said radial line, as shown by dot and dash lines in Fig. 2, so that when the extension member 22 is rotated counter-clockwise (Fig. 2) or to the left said axis of the spindle will incline in the direction of rotation.

Threaded in the ear 29^a on the extension member 22 is the adjusting thumb screw 30, having a collar 30^a on its stem below the threaded portion thereof adapted to compress a coil spring 31, the spring surrounding said stem below said collar and being anchored on the housing by means of stud 32, the end of the stem and said stud being separated by a space, whereby, when said adjusting screw is actuated a varying downward pressure may be brought to bear on the housing thereby rendering change-

able the pressure of the edging wheel 28 upon the upper edge of the cylindrical supporting form 2.

As shown in Fig. 4 the outlet 25 passes through the inner wall of the casing 26 into the interior thereof where the escaping gas is ignited, the flame licking the edging wheel to suitably heat it to properly iron the edge of the collar. The periphery of the edging wheel is formed with a round-bottomed groove 33 at the base of a flange 34, said flange forming the outer edge of the wheel. The inner peripheral portion of the wheel is slanted upwardly from opposite sides to form the apex 35, which is rounded and adapted to engage, when said wheel is rolled, the cam 35', arranged within the form 2, whereby the housing D may be raised bodily from the upper edge of the form 2, for the purpose of avoiding the tab b which customarily is formed to extend beyond the finished edge of the collar, such as b (Fig. 6).

The collar a as indicated in the drawings is placed with its fold over the upper edge 90 of the form 2, the neckband thereof being within the form and the outer portion of the collar, overhanging the outer wall. In order to hold the collar in proper relative position, relative to said cam 35' a flat spring 36 secured on the outer wall of the form 2 is provided.

As shown in Fig. 6 the outer portion of the collar is caused to abut against the stop 37 of the spring, the spring gently impinging upon the collar to hold it in place. Thus, as the edging device is rotated the edging wheel will ride over the cam 35 and over the tab b of the collar, and then roll over the upper edge of the collar as shown, always under the influence of the pressure of the spring 31. In order to avoid undue shifting of collars of unusual shape and which may be projected outwardly to an unusual degree, a wiping flange 38 is provided on the housing, whereby any outward projecting collar portion may be engaged to push it inwardly without disturbing the position of the collar.

Fig. 7 represents a cross section of a collar 115 illustrating for clarity in exaggerated form, the customary construction of a double fold collar showing the plies as they are assembled and stitched together. It will be noted upon inspection of the drawing, that the ply c forming the inner wall of the neck band, is doubled upon itself inwardly, adjacent the upper folded edge of the collar. This forms a ridge close to the finished edge of the collar, which in poorly laundered 125 collars frequently stands out, forming a sharp rough edge as indicated in Fig. 8 at d. This is very annoying to the wearer, in that it cuts and abrades the skin.

Further when the heated iron is dragged 130

by friction over the surface the upper edge of the collar becomes polished. This is very objectionable where a dull finish is now required. In order to iron out any possible 5 roughness at the point *d* without also polishing the top edge of the collar, applicant tilts his edging wheel inwardly so that the flange 10 34 clears the outer face of the collar, and to effect a wiping movement from below upward over the projection *d*, so as to wipe it into flush relationship with the outer ply 9 of the collar as shown in Figs. 9 and 10. Applicant disposes his edging wheel at an 15 angle to a radial line cutting the center of the form 2, whereby the point of contact of the wheel with the collar is shifted behind the radial line relative to the direction of travel. Obviously, that half of the wheel 20 forward of a vertical line cutting the axis of rotation is traveling leftward, counter-clockwise and downward, and that other half of the wheel is traveling upward. The point of contact, as at 40 is within the upwardly moving half of the wheel as indicated 25 in Fig. 2. Thus there is a frictional upward engagement between the wheel and collar, as the housing is rotated about the shaft 4, polishing and rounding the collar at *d* as indicated in Fig. 10, the frictional 30 action changing to a rolling action before the top or visible portion of the collar is reached. It is to be remembered that collars before being subjected to the edging process are moistened along the upper edge, which 35 softens the fabric rendering it pliable so that the edge *d* may easily be pressed into flush relationship with the top part of the collar.

I claim:

40 1. A device of the class described, comprising a frame, a cylindrical collar supporting form axially vertically disposed on said frame and having a circular upper edge, a rotary device, mounted on the frame 45 and having its axis of rotation coincident with the axis of said form means for rotating said rotary device, and a grooved wheel rotatable on said rotary device and engaging with its groove said upper edge to roll 50 thereon when said rotary device is actuated, the axis of rotation of said grooved wheel being at an acute angle to said circular upper edge for the purpose set forth.

2. A device of the class described, comprising a frame, a collar supporting form on the frame, said form having a circular upper edge, a rotary device rotatably supported on the frame and rotatable in a horizontal plane above said supporting form 55 said rotary device being swingable in a vertical plane and including an ironing wheel adapted to roll with its periphery on said circular edge when said device is rotated, means for rotating said rotary device, and

spring means pressing outwardly between 65 said rotary device and the frame to press said wheel against said upper edge.

3. A device of the class described, comprising a frame, a cylindrical collar supporting form axially vertically disposed on 70 said frame, and having a circular upper edge, a rotary device, mounted on the frame, its axis of rotation coincident with the axis of said form, means for actuating said rotary device, and a peripherally grooved 75 wheel rotatably supported on said rotary device and adapted to roll with its groove on said circular edge, the axis of rotation of said grooved wheel being inclined to the vertical plane coincident to a radius of said 80 circular edge for the purpose set forth.

4. A collar ironing machine, comprising a frame, a circular collar support thereon, a rotary device including an ironing wheel 85 rotatable above the collar support and rotatably supported on the frame, said wheel being adapted to roll with its periphery on said circular collar support and said rotary device being swingable upwardly away from said collar support, and spring means be- 90 tween said rotary device and the frame whereby said wheel is pressed against said circular collar support, the pressure on said rotary device being supplied solely by said spring means. 95

5. A device of the class described, a frame, a cylindrical collar supporting form axially vertically disposed on said frame and having a circular upper edge, a rotary device on said frame, its axis of rotation coincident 100 with the axis of said form, means for actuating said rotary device, and rotary collar engaging means, rotatable on said rotary device; the axis of rotation of said rotary collar engaging means being at an angle 105 both laterally and vertically to said circular upper edge.

6. In a device of the class described, the combination with a frame, and a driven shaft on the frame, of a stationary collar 110 supporting form, a rotary collar engaging device rotatable on the frame and extending above said collar supporting form, a gear operatively connected with said collar engaging device, hand operable connecting 115 mechanism including a shifting lever for operatively connecting said gear to said shaft, and co-operating means on said shifting lever and said gear, whereby when said gear is operated, said collar engaging device will be rendered effective for a predetermined period of time and then automatically disconnected from said driven shaft. 120

In testimony whereof I affix my signature in presence of a witness.

CHARLES F. PHILLIPS.

Witness:

GEORGE VOELKER.
